UNITED STATES PATENT OFFICE.

WILLIAM T. SMITH, OF PHILADELPHIA, PENNSYLVANIA.

DESIGN FOR A RUG.

SPECIFICATION forming part of Design No. 18,712, dated October 30, 1883.

Application filed September 27, 1883. Serial No. 286,566. Term of patent 3½ years.

To all whom it may concern:

Be it known that I, WILLIAM T. SMITH, a citizen of the United States, residing at Philadelphia, in the county of Philadelphia and State 5 of Pennsylvania, have invented and produced a new and original Design for a Rug, of which the following is a specification, reference being had to the accompanying photographic print, forming a part thereof, which conveys to any 10 one skilled in the art of rug-weaving a clear understanding of the same, and is sufficient to enable such person to use my invention.

The design consists of a center panel ornamented by representations shown, and an ornamental border surrounding the whole, as 15 shown in the photographic print.

What I claim as my invention, and desire to secure by Letters Patent, is—

The design for a rug, consisting of a center panel ornamented by representations shown, 20 and an ornamental border surrounding the whole, as shown in the photographic print.
